UNITED STATES PATENT OFFICE.

JAMES W. NELSON, OF NEW YORK, N. Y.

HYDRAULIC JACK.

1,149,279.

Specification of Letters Patent. Patented Aug. 10, 1915.

Application filed November 26, 1909. Serial No. 530,031.

To all whom it may concern:

Be it known that I, JAMES W. NELSON, a citizen of the United States, and a resident of the city of New York, borough of Brooklyn, county of Kings, and State of New York, have invented certain new and useful Improvements in Hydraulic Jacks, of which the following is a specification.

This invention relates to hydraulic jacks, with more particular reference to the type of jack shown and described by me in an earlier Patent No. 874,698, dated December 24, 1907.

The principal object of the present invention is the provision of means for facilitating the operation of "lowering" the jack; *i. e.*, releasing the liquid which is confined under pressure in the ram chamber and permitting the same to flow back into the reservoir or other source of supply, whereby the expanded parts of the jack may be contracted for the next succeeding operation.

In my earlier patent aforesaid, I have shown and described an independent device for unseating the pump valves and thus providing an open passage from reservoir to ram chamber. Under some conditions, however, it is desirable that a jack be provided, in addition to this independent lowering mechanism, with means whereby the jack may be lowered by movement of the pump-lever through a distance somewhat in excess of the usual maximum effective pumping stroke. Furthermore, it is well known that the ram in this type of jack, as a rule, is made up of three separate parts; *viz.*, a cylinder closed at its lower end, a pump block in said cylinder, and a head to which said cylinder is secured, the last providing a reservoir for the liquid employed and containing the pump actuating mechanism. As these parts are usually secured together by screw-threaded connections, it will be apparent that their relative positions, when assembled, are not readily predeterminable. Therefore, with the valves in fixed locations after the parts of the jack have been assembled, and these locations being unpredeterminable with respect to the position of the head which also contains the valve actuating means, it will be apparent that such valve actuating means should be of such a character as to be operable irrespective of the positional relations of the

other parts of the jack hereinbefore recited.

My invention will be more readily understood by reference to the accompanying drawings, forming a part of this specification, in which—

Figure 1 is a central vertical section of a hydraulic jack embodying my invention; Fig. 2 is a section taken substantially on the line 2—2 of Fig. 1, and Fig. 3 is a section 65 on the line 3—3 of Fig. 1.

Referring now to the drawings in detail, numeral 6 refers to the ram cylinder which is provided with the heavy and preferably integral base 7. The ram comprises 70 the cylindrical member 8 which is bored to provide an upper pump chamber 9 near the bottom thereof and a lower pump chamber 10 of smaller diameter below the chamber 9. These pump chambers are sometimes provided by the insertion of a suitable pump-block in the bottom of the cylinder which provides the ram, although in this case I have shown an integral ram member.

The upper end of the member 8 is screw-threaded for the reception of the head 11 which is provided with a correspondingly screw-threaded seat therefor. This head 11 provides an interior chamber 12 for the liquid employed, and in this head is located the 80 pump actuating mechanism. This mechanism comprises a rock shaft 13 projecting to the exterior of said head, where it is provided with the usual pump-lever. Upon this shaft is secured the arm 14 which terminates in a knuckle 15 projecting into the head 16 to which the piston-rod 17 is secured. When said shaft 13 is rocked, therefore, said piston-rod will be vertically reciprocated. At the lower end of the rod 17 95 and snugly fitting within the chamber 9, is the piston 18 from the lower end of which projects an extension 19 of said piston-rod carrying a piston 20 snugly fitting and adapted to reciprocate in the chamber 10. 100

The ram member 8 is provided with a vertical bore 21 which at 22 is slightly enlarged in diameter to provide a seat for the valve 23 which has the stem 24 projecting upwardly in said bore. At 25, said bore is 105 again increased in diameter to provide a seat for the valve 26 which has a stem 27 projecting upwardly and extending nearly but under normal conditions not quite to the valve 23. In order to again reduce the 110

now increased diameter of said bore at the lower end thereof, I provide a removable cylindrical plug 28 which provides a seat for the valve 29 which has a stem 30 projecting upwardly and extending nearly but under normal conditions not quite to the valve 26. I prefer that the lower valve 29 should be spring-seated, as shown.

A lateral bore 30 connects the chamber 31 within the ram member 8 with the bore 21 above the valve 23. Another lateral bore 32 connects the chamber 9 below the larger pistons with said bore 21 between the valves 23 and 26. Similarly, a lateral bore 33 connects the chamber 10 below the small piston with the bore 21 above the lowest valve 29. It will be apparent that with each of these valves free to perform its usual function, upon the up-stroke of the piston-rod 17 partial vacuums will be created in the chambers 9 and 10 below the pistons 18 and 20, respectively, the inequalities of pressure resulting in the unseating of the valves 23 and 26 and a flow of liquid from the chamber 31, and the chamber 12 in the head 11, past said valves and into the chambers 9 and 10. Upon the down-stroke of the piston rod 17, the valve 23 will be seated by the excess of pressure underneath the same, and the liquid will be forced under pressure past the valve 29 and into the ram or pressure chamber 34.

Slidably mounted in the top of the chamber 31 in the ram chamber 8, is the cylinder 35, the upper end of which is provided with a flange or rim 36 which projects to both sides of the body portion of said cylinder, leaving a central aperture 37 for the piston rod 17 and to permit of the flow of liquid from the chamber 12 to the chamber 31. In the bore 21 is located a rod 40, the lower end of which is located in contact with or just above the upper end of the stem 24 of the valve 23. This rod 40 is upwardly spring pressed and normally held clear of the valve stem 24 by means of the spring 38, in compression between the shoulder 39 and the pin 41 in said rod, the upper end of said rod contacting with the flange or rim 36 of the cylinder 35 and serving to return the latter to normal position when it has been depressed. In the head 11 is mounted a short shaft 42 on the inner end of which is fixed the cam 43, located to act against the flange or rim 36 of the cylinder 35. At the outer end of the shaft 42 is provided a head 44 carrying a lever 45 by means of which the shaft 42 may be rotated to actuate the cam 43.

It will now be apparent that when it is desired to hold the upper valve 23 off its seat, as is necessary when it is desired to sacrifice speed for power under the well known principles of hydrostatics by decreasing the piston area, the lever 45 is turned to rotate the cam 43, which impinges against the

flange 36 and forces downwardly the rod 40 to the point where the valve 23 is unseated. Under these conditions, the liquid which is drawn into the chamber 9 upon the up-stroke of the piston, will upon the down stroke thereof follow the path of least resistance and flow idly back through the bore 32, past the valve 23 and through the bore 30 to the chamber 31. It will be furthermore apparent that all of the valves in said bore 21 may be unseated by depressing the rod 40 a sufficient distance that the valve 23 has impinged against the stem 27 and unseated the valve 26, which, in turn, impinges against the stem 30 and unseats the valve 29, all of these valves being in this manner held off their seats and providing an open passage from the ram chamber 34 to the reservoir 12, so that the liquid will flow back to said reservoir and the parts of the jack be again contracted for the next succeeding operation. It is obvious, of course, that the rod 40 may be depressed in this manner and to this extent by continued rotation of the cam 43, but inasmuch as this operation is entirely independent of the pumping operation and makes it necessary for the man who is operating the pump to release the pump lever and carefully turn the lever 45 through the proper arc, and inasmuch as the old method of lowering through manipulation of the pump lever itself would undoubtedly require less time, I provide the head 16 with a downwardly projecting pin 46 which, upon the normally effective stroke of the piston-rod, does not impinge against the flange or rim 36 of the cylinder 35, but which is of such length and so positioned on said head 16 that when the downward stroke of said piston-rod is increased beyond the normally effective stroke, the end of said pin 46 will impinge against said flange or rim 36 and depress the rod 40 in the manner described to successively unseat all of the valves in the bore 21.

It will be noted that the bore 21 is permanently positioned with respect to the other parts of the ram member 8. It will also be noted that the cam 43 and its actuating mechanism and the pin 46 are permanently positioned with respect to the other parts of the head 11. It will furthermore be noted that when the ram member and its head are secured to each other by a screw-threaded connection—which has been found to be by all means the preferable form of connection—it is impossible, or at least utterly impracticable, to cut screw-threads in such a way as to predetermine the ultimate positional relation of the two parts when connected together. Therefore, with a permanently positioned valve-actuating rod in one member, and permanently positioned means for actuating said rod in the other member,

which members cannot be secured together in such a manner as to insure these parts being brought into proper coöperative relation, it is of the greatest importance that some means be interposed between said rod and its actuated means which will insure operation of said rod entirely irrespective of the positional relation of the ram member to the head which is mounted thereon. It will therefore be apparent that in providing the flanged cylinder 35, the flange of which in any position of rotation impinges against the upper end of the rod 40 and receives the action of the cam 43 and is in position to be engaged by the pin 46, I have provided means whereby one or more of the valves in the bore 21 may be unseated by means of the lever 45 or by means of the pump lever, irrespective of the positional relations of the ram member 8 to the head 11.

Having thus described a practical and convenient embodiment of my invention, I claim as new and desire to secure by Letters Patent:

1. In a hydraulic jack, the combination, with a ram comprising a body portion and head secured thereto in non-predeterminable positional relation, said body portion containing the pump valves and a rod acting against one of said valves to unseat said valve only or all thereof, and said head being provided with means for actuating said rod, of means interposed between said actuating means and said rod to insure coöperative action irrespective of the relative positions of said body portion and said head.

2. In a hydraulic jack, the combination, with a ram comprising a body portion and a head secured thereto, said body portion containing the pump valves and means for their manual control, and said head containing the pump actuating mechanism and being provided with independent means for actuating said valve controlling means, of interposed means for insuring coöperative action between said independent actuating means and said controlling means and for actuating said controlling means from the pump mechanism, irrespective of the relative positions of said body portion and said head.

3. In a hydraulic jack, the combination, with a ram comprising a body portion and a head secured thereto, said body portion containing the pump valves and a rod acting against one of said valves to unseat said valve only or all thereof, and said head containing the pump actuating mechanism and being provided with independent means for actuating said rod, of interposed means for insuring coöperative action between said independent actuating means and said rod and for actuating said rod from the pump mechanism, irrespective of the relative positions of said body portion and said head.

4. In a hydraulic jack, the combination,

with a ram comprising a body portion and a head secured thereto, said body portion containing the pump valves and means for their manual control and said head containing the pump actuating mechanism which is also provided with means for actuating said valve-controlling means, of interposed means for insuring coöperative action between said valve controlling means and both of the actuating means therefor irrespective of the relative positions of said body and said head.

5. In a hydraulic jack, the combination, with a ram comprising a body portion and a head secured thereto in non-predeterminable positional relation, said body portion containing the pump valves and means for their manual control and said head containing the pump actuating mechanism which is also provided with means for actuating said valve-controlling means, of interposed means for insuring coöperative action between said valve controlling means and both of the actuating means therefor irrespective of the relative positions of said body and said head.

6. In a hydraulic jack, the combination, with a ram comprising a body portion and a head secured thereto, said body portion containing the pump valves and a rod acting against one of said valves to unseat said valve only or all thereof, and said head containing the pump actuating mechanism which is also provided with means for actuating said rod, and said head being further provided with independent means for actuating said rod, of interposed means for insuring coöperative action between said rod and both of said actuating means irrespective of the relative positions of said body portion and said head.

7. In a hydraulic jack, the combination, with a ram comprising a body portion and a head secured thereto in non-predeterminable positional relation, said body portion containing the pump valves and a rod acting against one of said valves to unseat said valve only or all thereof, and said head containing the pump actuating mechanism which is also provided with means for actuating said rod, and said head being further provided with independent means for actuating said rod, of interposed means for insuring coöperative action between said rod and both of said actuating means irrespective of the relative positions of said body portion and said head.

8. In a hydraulic jack, the combination, with a ram comprising a body portion and a head secured thereto, said body portion containing the pump bore and a series of interdependently controlled pump valves, of a rod acting against one of said valves to unseat said valve only or all of said valves, a cylinder slidable in said bore and adapt-

ed upon depression to depress said rod, and means in said head for depressing said cylinder.

9. In a hydraulic jack, the combination, with a ram comprising a body portion and a head secured thereto, said body portion containing the pump bore and a series of interdependently controlled pump valves, of a rod acting against one of said valves to unseat said valve only or all of said valves, 10 a cylinder slidable in said bore and having

a flange projecting over the upper end of said rod, and means in said head acting against said cylinder to depress the same.

In testimony of the foregoing, I have 15 hereunto set my hand in the presence of two witnesses.

JAMES W. NELSON.
